MULTI-TANK AQUARIUM

Richard H. Hayward, 10331 SW. 56th St.,
Miami, Fla. 33165

Filed July 15, 1966, Ser. No. 3,092

Term of patent 14 years

(Cl. D91—2)

FIG. 1

FIG. 2

FIG. 3

FIG. 4

FIG. 1 is a front elevational view of a multi-tank aquarium showing my new design.

FIG. 2 is a top plan view thereof.

FIG. 3 is an elevational view taken from one end thereof, the opposite end being the same as the end shown.

FIG. 4 is a rear elevational view thereof.

The broken lines shown in FIG. 4 are for the purpose of illustration only.

I claim:

The ornamental design of a multi-tank aquarium, as shown and described.
